UNITED STATES PATENT OFFICE.

MICHAL TYMCZYNA, OF CALDER, SASKATCHEWAN, CANADA.

ADJUSTABLE STAND.

1,293,253.

Specification of Letters Patent.

Patented Feb. 4, 1919.

Application filed July 2, 1918. Serial No. 242,999.

To all whom it may concern:

Be it known that I, MICHAL TYMCZYNA, a subject of the Emperor of Austria, residing at Calder, Province of Saskatchewan, and 5 Dominion of Canada, have invented certain new and useful Improvements in Adjustable Stands, of which the following is a specification.

This invention relates to improvements in 10 furniture and particularly to adjustable stands and has as its special object the provision of means whereby the upper surface of the stand may be raised or lowered with relation to the base.

15 A further object is to provide means whereby such adjustment may be secured in an expeditious and easy manner, the parts being held securely when in adjustment.

These and other like objects are attained 20 by the novel construction and combination of parts hereinafter described and shown in the accompanying drawing, forming a material part of this disclosure, and in which:—

25 Figure 1 is a side elevational view showing a stand or table made in accordance with the invention.

Fig. 2 is a vertical sectional view taken 30 substantially on line 2—2 of Fig. 1, and

Fig. 3 is a fragmentary transverse sectional view, taken on line 3—3 of Fig. 2.

The stand or table comprises a hollow support 10, here shown to be of rectangular cross-section, with which is rigidly engaged 35 the legs 11, carried on casters 12 as is usual so that the article may be readily moved over a relatively level surface.

The upper part of the stand is here shown 40 to be formed with a concave or cup shaped head 14, having downwardly extending side flanges 15, which, like the standard, are indicated to be rectangular in cross-section.

A downwardly projecting boss or hub 16 45 is formed with the lower surface of the concave element 14, and has rigidly engaged to it at one side, by means of a plate 17 the upper end of a bar 18, the same extending downward through a cover 19 formed with the standard, into the space therebelow 50 where it is received telescopically within a guide tube 20, so as to freely move vertically therein.

Engaged in the other side of the hub 16, 55 and held by the plate 17, is a head 21 of a rectangular bar 22, one of its faces being provided with teeth 23, in the manner of

a rack, the same also extending downward through an opening in the cover plate 19.

Engaged at the outer upper end of the telescopic guide tube 20, is a band 25, having 60 a lateral projection 26, which is pivoted by the pin 27, to the forked ends 28 of a rod 29, the same extending outward through a hollow projection 30, formed upon one side at the top of the standard 10, and secured to 65 the extending end of the rod 29, is a knob 32, between the inner part of which and the lower end of the recess in the projection 30, is a compression spring 33 adapted to normally hold the rod outward. 70

Also secured to the band 25, at the lower portion thereof, is an arm 35, having a blade like detent 36, adapted to engage in the spaces between the teeth 23 of the rack when the rod 29 is pressed outwardly, due to the 75 compression of the spring 33, by actuating the knob 32.

In operation, it being desirable to either raise or lower the head or top 15 of the stand, the knob 32 is pressed inwardly overcoming 80 the effect of the spring, thereby rotating the band 25 and withdrawing the detent 36, from the rack and permitting the upper portion of the stand to be raised or lowered as may be desired, while immediately upon releasing the knob 32, the spring acts to force 85 the detent into position, holding the top of the stand in adjustment.

From the foregoing it will be seen that an effective device has been presented whereby 90 the upper portion of the stand may be readily raised or lowered and when in any adjusted position that it is securely locked against displacement.

Having thus described my invention what 95 I claim as new and desire to secure by Letters Patent, is:

In an adjustable stand, the combination with a rectangular base, legs radially attached to said base extending outward therefrom, a top engageable over said base, a bar secured in the lower surface of said top, said bar extending downward into said base, a telescopic guide tube mounted vertically in said base in which said bar operates, a 100 rack bar parallel thereto, the teeth of said rack bar extending outward to one side, a band rotatably engaged upon said guide tube, an arm formed with said band, a detent extending outward from said band, said 105 band being engageable with the teeth of said rack, a rod slidably transversely in said 110

hollow base, one of the ends of said rod being connected to said detent whereby it may be operated, a knob secured to the outer end of said rod, a spring interposed between said rod and said base whereby said rod is held normally outward, and means operative

said detent is removed from the teeth of said rack permitting said top to be moved up or down relative to said base.

10

In testimony whereof I have affixed my signature.

MICHAL TYMCZYNA.
